Application September 16, 1932, Serial No. 633,440

15 Claims. (Cl. 214—138)

This invention relates to a novel form of excavating machine wherein control of the movement of the same is greatly improved in a novel manner.

5 It is the purpose of this invention to arrange the elements of an excavating machine, wherein a dipper and stick assembly is pivoted to the boom, so that relative movement of the dipper stick assembly with respect to the boom is restrained in certain desired positions. It is the purpose of the machine of this invention to prevent destructive engagement of the parts of the machine and to do the same by employing the forces causing engagement to produce the necessary restraint. It is a further purpose of this invention to cause the energy released upon restraining an engagement, to be absorbed by friction members capable of absorbing such energy without the destruction thereof. A further purpose of this invention is to provide a machine with all of the above advantages and at the same time having equal range and facility of movement as compared with machines of a similar type formerly known.

20 In all excavators of the type here involved, the prevention of shock upon full extension of the dipper is a problem of importance. Many means have been proposed and some are in use for preventing this shock. In some of these constructions, sufficient clearance is provided so that the dipper and stick assembly can move beyond the line of pull of the hoisting line. The amount of clearance which can be provided in this fashion without curtailing the effectiveness of the machine for digging is limited and the difficulty usually encountered in such means lies in the fact that the dipper and stick assembly is carried by inertia, at times, beyond the line of pull of the hoisting line and the limited clearance provided 25 is of no use in preventing a violent and destructive engagement of the parts. In other constructions collision of the parts is not prevented but is rather, lessened or minimized by various forms of shock absorbing buffers. The buffers employed 30 in these constructions are composed of resilient material and unusually heavy shocks exceed the protecting power of these buffers when they are made soft enough to protect against smaller and more frequent shocks. Real protection of 35 the machine against every contingency cannot be provided by the use of resilient buffers.

By means of this invention, restraint metered to the magnitude of the shock to be resisted is provided by utilizing the tension in the hoisting line to produce the restraint. When the hoist-

ing line of the machine of this invention is wound in and the digging line paid out, the dipper and stick assembly moves in an arc to a position approximately parallel with and adjacent to the boom. In the latter stages of this action the motion is restrained by means which engage the hoisting line and deflect the same. The magnitude of this restraint is related to the tension in the hoisting line and in view of the fact that the violence of the outward movement of the dipper and stick assembly is also directly related to the tension in the hoisting line, in fact caused thereby, the dipper and stick assembly comes to rest with respect to the boom at a balance point.

Upon reference to the accompanying drawings 15 and the explanation that follows, the construction of the machine of this invention and the manner in which the foregoing and other advantages are obtained, will be quite apparent.

In the accompanying drawings, Fig. 1 shows a 20 side view of a pull shovel embodying this invention;

Fig. 2 is a diagrammatic showing in perspective of a portion of the rigging of the hoisting line;

Fig. 3 is a side view of the outer portion of the 25 boom and the dipper and stick assembly, showing the latter pulled to the extreme inner position;

Fig. 4 is a side view of the outer portion of the boom and the dipper and stick assembly showing the latter in full lines in an extended position and in dotted lines in an intermediate position;

Fig. 5 is a front view of the winding drum used in controlling the hoisting line;

Fig. 6 is a side view of another form of the machine of this invention;

Fig. 7 is a side view of another simplified form of the machine of this invention.

The machine shown in Fig. 1 is mounted upon a conventional rotating base crane body 1. Employed in the construction are the mast 2, the boom 3, the dipper 18, the stick 4, the hoisting line 5 and the digging line 6. The hoisting line 5 extends from the winding drum 7 over sheave 8 in the top of mast 2, outwardly over sheave 9 40 mounted upon the boom 3 returning to sheave 10 likewise mounted on the mast and then upwardly over the sheave 11, not shown in Fig. 1 but appearing clearly in Fig. 2, thence over sheave 12 not appearing in Fig. 1 but shown clearly in Fig. 2 toward the outer end of the boom. Hoisting line 5 passes the guiding member 13 mounted 45 on the tip of the boom and is then bent about the heel sheave 14 mounted upon the rear of the dipper 18. Hoisting line 5 then extends past 50 Fig. 2 toward the outer end of the boom. Hoisting line 5 passes the guiding member 13 mounted on the tip of the boom and is then bent about the heel sheave 14 mounted upon the rear of the dipper 18. Hoisting line 5 then extends past 55

the guiding member 13 and the bearing sheave 15 to an anchorage 16 on the lower side of the boom 3 which anchorage is spaced a short distance from the dipper stick pivot 17. The digging line 6 extends from the winding drum 19 over the guide sheaves 20 and 21 mounted on the boom and from there to a padlock sheave 22 pivotally secured to the dipper and from thence to a mounting guide directly behind guide sheave 21 and not shown to an anchorage 23 shown in dotted lines on the boom.

By operating winding drum 7 to pay out hoisting line 5 and by operating winding drum 19 to draw in the digging line 6, the dipper and stick assembly 4 may be moved from the position shown in Fig. 1 through a series of intermediate positions such as is shown in dotted lines in Fig. 4 to the position shown in Fig. 3. By holding winding drum 19 fast and by operating winding drum 7 to take in the hoisting line 5, the entire boom and dipper may be elevated and by combinations of these manipulations, a wide range of excavating movements may be executed including both the loading and the discharging of the dipper.

In forming an excavation of maximum depth the dipper 18 and stick 4 may be extended as shown in Fig. 1, and in this position digging line 6 is ordinarily permitted for a moment to be slack. In this condition the moment imposed upon the dipper stick assembly by the hoisting line 5 urges the dipper stick assembly to move toward the outer end of the boom and to close with it. This moment is small due to the short lever arm upon which it is applied, but this moment is large compared to the rather smaller opposing tendency imposed by gravity when the machine is in this position. The hoisting line 5, however, is brought to an anchorage 16 beneath the boom and passes under tension over the bearing sheave 15. As shown in Fig. 1 the hoisting line 5 is deflected by the bearing sheave 15. This deflection is the measure of a new moment which opposes movement of the dipper and stick assembly toward the boom. It will be seen that in this condition there are two opposing moments, both born of the tension in the hoisting line 5. It will also be apparent that due to the short spacing of anchorage 16 and guide sheave 13, the moment opposing the upward movement will increase far more rapidly than the moment urging the upward movement. Therefore, regardless of the degree to which the tension in hoisting line 5 is increased, there is a limiting position of the dipper and stick assembly with respect to the boom, in which position the dipper and stick assembly will come to a state of rest. The provision of spring or resilient buffers to prevent shock is therefore unnecessary. However, if desired, such buffers can be employed in conjunction with this invention and will find a limited usefulness therein.

Another important advantage of the machine of this invention resides in the property of the device to yield to certain very violent forces without destruction of the machine. It is possible to wind the hoisting line 5 of the machine of this invention as rapidly as desired and upon the completion of the outer movement of the dipper stick assembly the same is brought to rest without destructive effect through the functioning of certain elements of the machine which are thoroughly capable of absorbing the energy released. Should the dipper stick assembly be swung outwardly with considerable speed to the position shown in Fig. 4, the kinetic energy of this out-

ward movement must be absorbed when the dipper stick assembly is brought to rest. This is accomplished in the machine of this invention because the deflection of the hoisting line 5 by the bearing sheave 15 calls for a lengthening of the cable. With cables commonly employed, the strength is so great that an enormous force would be required to stretch the cable enough to provide this necessary lengthening. Before such an extreme force becomes established a slipping of the hoisting brake 24 shown in Fig. 5 or hoisting drum driving clutch 25 actually occurs and absorbs the released energy. The brake 24 and clutch 25 are both designed to absorb energy and the dipper stick assembly is brought to rest thereby without destructive action on any part of the machine.

Referring to Fig. 4 the boom end assembly may be considered as being composed of a movable dipper 18, a stick 4 pivotally connected to the boom 3, a digging line 6 for causing inward movements, and a hoisting line 5 for causing outward movements and an indistinguishable portion of the hoisting line 5 acting as a sort of bridle. A construction embodying this invention which shows that the bridle portion of the hoisting line may sometimes be a more or less distinct element is shown in Fig. 6. In this figure is shown a dipper 18' secured to a stick 4', the latter being pivotally mounted on the boom 3' at pivot 17'. Pivotally mounted on the dipper 18' is the bell crank 30. Hoisting line 5' is attached to the outer arm of bell crank 30 and passes over the guide member 13' and from there to an appropriate winding drum. Secured to the boom at anchorage 16' and extending to the inner arm of the bell crank 30 is the bridle line 31. The operation of this form of the machine of this invention is exactly similar to the form shown in Fig. 4. For example in bringing the dipper and stick assembly to an extended position, a restraining sheave 15' engages the bridle line 31 deflecting the same. The tension in the bridle line 31, however, is caused by tension in hoisting line 5' and the restraint caused thereby is metered to the tension in the hoisting line. The bridle line 31 may however be considered as no more than an extended portion of the hoisting line 5'.

In the forms described herein, the point of engagement of the hoisting line 5 or 5' with the dipper 18 or 18' is displaced from the pivot 17 or 17', a distance considerably greater than the displacement of guide members 13 or 13'. Upon extension of the dipper, the bridle line 31 or bridle portion of hoisting line 5 extends beyond the guiding member 13 or 13' on the tip of the boom as shown in Figure 4. Further outward movement of the dipper and stick assembly produces a second deflection in the bridle at the guide member 13. This second deflection provides an additional restraint upon the outward movement of the dipper and stick assembly and comes into play in effecting the control of exceptionally severe outward movements.

In Fig. 7 is shown a simplified form of the machine of this invention. In this construction, a dipper 18" mounted upon a dipper stick 4" is dependently pivoted at pivot 17" from boom 3". Boom 3" is provided at its outer extremity with guide sheave 13". Hoisting line 5" passes about a heel sheave 14" mounted on the dipper 18" and then passes to an anchorage 16" which in this construction, is secured to the dipper stick 4". As shown in Fig. 7, the bridle portion of hoisting line 5" is deflected by guide member 75

13" when the dipper and stick assembly are moved to extended position.

As shown in Figs. 1 and 2 the hoisting line 5 is arranged so that a portion of the weight of the boom is carried by sheave 9. With this arrangement tension in hoisting line 5 is materially reduced and the problem of controlling the outward movement of the dipper is somewhat lessened. However, the hoisting line 5 may connect the boom end assembly directly with the winding means and operate successfully in this manner.

Hereafter in the claims the heel sheave 14 or bell crank 30 or any equivalent means will be referred to as a hoist mounting.

We desire it to be understood that this invention is not to be limited to any particular form or arrangement of parts except in so far as such limitations are included in the claims.

20 What we claim as our invention is:

1. In an excavating machine, the combination with a boom and a dipper and stick assembly connected to said boom and movable with respect thereto, of a hoisting line connected to said dipper and stick assembly, and means adapted to engage said hoisting line when the dipper stick is brought into an outwardly extended predetermined position with relation to said boom, whereby said hoisting line will serve to absorb shocks caused by the relative movement of said boom and dipper and stick assembly.

2. In an excavating machine, the combination with a boom and a dipper and stick assembly connected to said boom and movable into substantial alignment therewith, of a hoisting line connected with said dipper and stick assembly, and means adapted to engage said hoisting line when the dipper and stick assembly is brought into substantial alignment with said boom, whereby said hoisting line will serve to absorb shocks caused by the relative movement of said boom and dipper and stick assembly.

3. The boom end assembly of an improved pull shovel which comprises a boom, a dipper and stick assembly pivotally mounted thereon, a hoisting line engaging said dipper and stick assembly, a bridle line tensioned by said hoisting line, connecting said boom to said dipper and stick assembly, means mounted upon said dipper and stick assembly for deflecting said bridle line when said dipper and stick assembly is moved to extended position, and a digging line engaging the inner side of said dipper and stick assembly.

55 4. The boom end assembly of an improved pull shovel which comprises a boom, a dipper and stick assembly pivotally mounted thereon, a hoist mounting on the heel of said dipper, a hoisting line engaging said hoist mounting, a bridle line also engaging said hoist mounting and anchored adjacent said pivot on the boom, means mounted upon said dipper and stick assembly for deflecting said bridle line when said dipper and stick assembly is moved to extended position, and a digging line engaging the inner side of said dipper and stick assembly.

5. The boom end assembly of an improved pull shovel which comprises a boom, a dipper and stick assembly pivotally mounted thereon, a hoist mounting on the heel of said dipper, a hoisting line engaging said hoist mounting, a bridle line also engaging said hoist mounting and anchored adjacent said pivot on the boom, means for deflecting said bridle line when said dipper and

stick assembly is moved to extended position, and a digging line engaging the inner side of said dipper and stick assembly.

6. The boom end assembly of an improved pull shovel which comprises a boom, a dipper and stick assembly pivotally mounted thereon, a hoist mounting on the heel of said dipper, a hoisting line engaging the hoist mounting on said dipper and extending to an anchorage under said boom, means mounted upon said dipper and stick assembly for deflecting said hoisting line between the hoist mounting on the dipper and the anchorage under the boom when said dipper and stick assembly is moved to extended position, and a digging line engaging the inner side of said dipper and stick assembly.

7. The boom end assembly of an improved pull shovel which comprises a boom, a dipper and stick assembly pivotally mounted thereon, a hoist mounting on the heel of said dipper, a hoisting line engaging the hoist mounting on said dipper and extending to an anchorage under said boom, means for deflecting said hoisting line between the hoist mounting on the dipper and the anchorage under the boom when said dipper and stick assembly is moved to extended position, and a digging line engaging the inner side of said dipper and stick assembly.

8. The combination with a movable boom mounted upon a winch support, of a dipper and stick assembly dependently pivoted below the boom near the outer extremity thereof, a hoist mounting upon the dipper, a guide member mounted at the tip of the boom, a hoisting cable passing outwardly above the boom from the winch support through the guide member on the boom, thence about the hoist mounting on the dipper to an anchorage on the boom, a restraining means mounted upon the stick in position to deflect the hoisting line intermediate the hoist mounting and the anchorage when the dipper and stick assembly is extended, and a digging line passing outwardly from the winch support to engagement with the inner side of the dipper.

9. The combination of a movable boom mounted upon a winch support, winding means on the winch support including friction driving and arresting means, a dipper and stick assembly dependently pivoted below the boom near the outer extremity thereof, a hoist mounting upon the dipper, a guide member mounted at the tip of the boom, a hoisting cable passing outwardly above the boom from one of the winding means on the winch support through the guide member on the boom, thence about the hoist mounting to an anchorage, a restraining means mounted upon the stick in position to deflect the hoisting line intermediate the hoist mounting and the anchorage when the dipper and stick assembly is extended, and a digging line passing outwardly from the winch support to engagement with the inner side of the dipper.

10. The combination of a movable boom mounted upon a winch support, winding means on the winch support including friction driving and arresting means, a dipper and stick assembly dependently pivoted below the boom near the outer extremity thereof, a hoist mounting upon the dipper, a guide member mounted at the tip of the boom, a hoisting cable passing outwardly above the boom from one of the winding means on the winch support through the guide member on the boom, thence about the hoist mounting to an anchorage, a restraining means for deflecting the hoisting line intermediate the hoist mounting

and the anchorage when the dipper and stick assembly is extended, and a digging line passing outwardly from the winch support to engagement with the inner side of the dipper.

- 5 11. An improved pull shovel which comprises a winch support, a movable boom mounted thereon, frictionally driven and arrested winding means mounted on the winch support, a dipper and stick assembly pivotally mounted on the boom, a hoisting line connected with one of the winding means on the winch support and engaging said dipper and stick assembly, a bridle line tensioned by said hoisting line connecting said boom to said dipper and stick assembly, means mounted upon said dipper and stick assembly for deflecting said bridle line when said dipper and stick assembly is moved to extended position, and a digging line engaging the inner side of said dipper and stick assembly.
- 10 12. The combination of a movable boom mounted upon a winch support having a mast, a dipper and stick assembly pivotally mounted on the boom, a heel sheave mounted upon the dipper, a guide member mounted at the tip of the boom, a lifting sheave mounted near the mid point of the boom, a hoisting cable passing from the winch support over the mast, about the lifting sheave back to the winch support, again over the mast, then through the guide member on the boom, thence about the heel sheave on the dipper to an anchorage on the boom, a restraining sheave mounted upon the stick in position to deflect the hoisting line intermediate the heel sheave and the anchorage when the dipper and stick assembly is extended, and a digging line passing outwardly from the winch support to engagement with the inner side of the dipper.
- 15 13. A boom end assembly of an improved pull shovel which comprises a boom, a dipper and

stick assembly pivotally mounted thereon, a hoist mounting on the heel of said dipper, a hoisting line engaging the hoist mounting and extending to an anchorage under said boom, a guiding means mounted upon said boom to deflect said hoisting line between the hoist mounting on the dipper and the anchorage on the boom when said dipper and stick assembly is moved to extended position, and a digging line engaging the inner side of said dipper and stick assembly.

- 20 14. In a pull shovel, the combination of a boom, a dipper and stick assembly pivotally dependent from the boom near the extremity thereof, a guiding member mounted upon the extremity of the boom, a hoist mounting upon said dipper and disposed beyond said guiding member when said dipper is in an outwardly projected position, a hoisting line engaging said hoist mounting and anchored inwardly of the outer end of said boom with a portion between its anchorage and said hoisting mounting movable into contact with said guiding member to check the movement of said dipper and stick assembly when said assembly is moved to extended position substantially lengthwise of the boom and away from the pivotal mounting thereof.
- 25 15. A boom end assembly of an improved pull shovel which comprises, a boom, a dipper and stick assembly pivotally dependent from the boom near the extremity thereof, a guiding member mounted upon the extremity of the boom, a hoist mounting upon said dipper, a hoisting line engaging said hoist mounting and anchored to the dipper stick in position to be deflected by said guiding member when said dipper and dipper stick assembly is moved to extended position.

PAUL BURKE.
ARTHUR ORLOFF.
